UNITED STATES PATENT OFFICE.

WILLIAM THOMAS BUCKINGHAM ROBERTS, OF LEICESTER, ENGLAND, ASSIGNOR, BY MESNE ASSIGNMENTS, TO UNITED SHOE MACHINERY CORPORATION, OF PATERSON, NEW JERSEY, A CORPORATION OF NEW JERSEY.

SEWING MACHINE.

1,391,978.

Specification of Letters Patent. Patented Sept. 27, 1921.

Application filed November 17, 1916. Serial No. 131,905.

To all whom it may concern:

Be it known that I, WILLIAM T. B. ROBERTS, a subject of the King of Great Britain, residing at Leicester, in the county of 5 Leicester, England, have invented certain new and useful Improvements in Sewing-Machines; and I do hereby declare the following to be a full, clear, and exact description of the invention, such as will enable 10 others skilled in the art to which it appertains to make and use the same.

This invention relates to sewing machines, particularly adapted for use in the manufacture of boots and shoes, of the type in which 15 a thread to be drawn through the work is passed around a hooked or barbed needle by a looper, and is especially applicable to machines of the class known as welt and turn shoe sewing machines.

20 Usually in machines of the class indicated, a curved needle is looped by an arm carrying at its end a passage in the form of a short tube, through which the thread passes, this arm being operated to lay the 25 thread around and into the barb of the needle for each stitch. In case of a breakage of the thread, which is caused generally by contact of the needle or thread with lasting tacks, it is almost invariably necessary 30 for the operator to re-thread the looper by hand, because the loose end of the thread has been pulled out of the looper-passage by the take-up devices. This re-threading obliges the operator to put down the work 35 and causes considerable loss of time.

The primary object of the present invention is to provide a looper re-threading mechanism which will minimize the loss of time required in hand labor. Accordingly 40 one feature of the invention contemplates the provision in a sewing machine of the type indicated of automatic means for performing the looper re-threading operation, preferably by opening the thread passage of 45 the looper at its side and passing the thread into such open passage, which is thereafter closed and the looper operated in the usual manner. In the illustrated embodiment of the invention, the looper threading mechanism 50 is locked in inoperative position during the sewing operation and the sewing mechanism is brought to a stop and locked in inoperative position while the looper threading mechanism is in operation.

Other features of the invention consist in 55 certain details of construction and combinations of parts, the advantages of which will be obvious to those skilled in the art.

The various features of the invention are 60 illustrated in the accompanying drawings, in which—

Figure 1 is a view in front elevation of a welt and turn wax thread sewing machine embodying the preferred form of the invention; 65

Fig. 2 is a view in side elevation, partly in section, of the machine shown in Fig. 1;

Fig. 3 is a detail view in front elevation of the looper threading mechanism;

Fig. 4 is a view in side elevation of the 70 parts shown in Fig. 3;

Fig. 5 is a diagrammatic view illustrating the mechanism for locking the looper threading mechanism in inoperative position and the devices for releasing the tension; 75

Fig. 6 is a detail view, partly in section, of the improved looper;

Fig. 7 is a horizontal section of the looper thread passage taken on the line 7—7 of 80 Fig. 6;

Fig. 8 is a vertical sectional view of the improved thread tension; and

Fig. 9 is a vertical section of the thread tension taken on line 9—9 of Fig. 8. 85

The welt and turn sewing machine illustrated in the drawings is substantially the same in its construction and operation of parts as the sewing machine shown in the patent to Eppler No. 1,108,560, dated August 25, 1914. This machine is provided with the usual curved hook needle 10, looper 12, thread finger 14, work support 16, awl 18, and channel guide 20, all of which, with the exception of the looper, have substantially 90 the same construction and mode of operation as the parts shown and described in the Eppler patent. 95

The machine illustrated in the drawings is provided with an automatic looper threading mechanism, which mechanism embodies the present invention in its preferred form, and consists of devices for opening and closing the looper thread passage, a thread clamp for holding the free end of the thread, 100 a threading arm for engaging the thread extending from the take-up roll to the thread clamp and placing the thread in the 105

looper thread passage, and means for operating these members.

The looper 12 (Figs. 1, 3, 4, 6 and 7) has the same general shape as the looper shown 5 in the Eppler patent, and is adjustably mounted in a carrier 24 which is pivoted to the usual slide 26. The upper end of the carrier 24 is provided with a slidingly mounted pin 28 which receives a pin on the 10 end of a rocking lever 30. The motion imparted to the looper by the lever 30 and slide 26 is the same as that imparted to the looper of the Eppler patent. The looper consists of a fixed section 32 and a movable 15 section 34, the lower ends of which are shaped to form a thread passage which is opened when the section 34 is moved away from the section 32. The thread passage is opened along planes which are preferably 20 formed tangentially to the thread passage, and project from the thread passage in a direction opposite to that in which the thread moves around the passage while it is being placed around the needle and 25 into the barb of the needle. With this construction each section of the thread passage is provided with a short face 36 and a long face 38, and the joints of the two sections are so arranged that they will not 30 catch or break the thread as it moves around the thread passage. The section 34 is normally held in a position to close the thread passage by means of a wedge 40 which is mounted within the shank of the looper. 35 When the wedge is withdrawn from the section 34, the section is moved into position to open the thread passage by means of a spring-pressed plunger 42 which is mounted in the section 32. To operate 40 the wedge 40 for opening and closing the thread passage, the upper end of the wedge is engaged by an operating rod 44 which is slidably mounted at the side of the carrier 24. The rod 44 is normally held in a position 45 to hold the thread passage closed by means of a tension spring 46 which is connected between a pin 48 in the machine frame and a pin 50 in the rod 44. To open the thread passage the rod 44 is lifted by means of a 50 lever 52 (Figs. 1 and 2) which positively withdraws the wedge 40 from the movable section 34. The lever 52 is pivoted to the machine frame and has one arm which engages an offset end 54 of the rod 44 and a 55 second arm which carries a cam roll 56. The cam roll 56 is held in engagement with a face cam 58 on the edge of a cam disk 60 by means of a tension spring 62 which is connected between the lever 52 and the machine frame. 60 When the thread passage of the looper is open the thread may be placed in the passage by means of the threading arm 63 (Figs. 1, 2, 3 and 4) which has a hook 64 65 on its lower end for engaging the thread after the free end of the thread has been clamped as hereinafter described. The upper end of the threading arm is movably mounted at one side of a cam plate 66 and is attached by a pair of screws 68 to a 70 clamping plate 70 mounted at the opposite side of the cam plate 66. Between the thread arm 63 and clamping plate 70 a pair of rolls 72 are mounted on the screws 68 and move in a cam groove 74 formed in 75 the plate 66. The clamping plate 70 is connected by means of a link 76 with a cam lever 78 which is mounted on a pivot 80 secured in an auxiliary machine frame 82. A cam roll 84 is mounted near the upper 80 end of the cam lever 78 and works in a cam groove 86 formed on the face of the cam disk 60. The cam disk 60 is fixed on a shaft 88 which is journaled in the auxiliary frame 82. The connection between the link 76 85 and lever 78 is adjustable to permit the threading finger to be properly timed in its operation. With the above construction the hook of the threading arm 63 carries the thread down between the machine frame 90 and looper and directly behind the looper. The lower end of the cam groove 74 has a comparatively sharp turn so that when the threading hook has passed the lower end of 95 the looper the thread arm is moved outwardly to place the thread against the face 88 of the thread passage in the section 32 of the looper. The thread is held in this position by the thread arm until the wedge 40 is moved down to close the looper thread 100 passage.

While the thread arm is drawing down the thread to thread the looper, the free end of the thread is held by the thread clamp 90 (Figs. 2, 3 and 4) which consists of a 105 lever pivoted to a bracket 92 projecting from the machine frame. The upper end of the lever 90 is connected by means of a link 94 with a double-arm lever 96, 98, which is pivoted to the machine frame. 110 The arm 98 of the lever is provided with a cam roll 100 (Fig. 2) which works in a cam groove 102 formed in the face of a gear wheel 104. The gear wheel 104 is fixed to the shaft 88 so that it will rotate the cam 115 disk 60. During the sewing operation the lower end of the thread clamp is held in the path of the thread and has an opening 106 through which the thread passes in going to the sewing point. One side of the opening 106 is closed by a leaf spring 108 (Fig. 3) so that the thread may be easily placed in the opening. When the thread is broken it will generally be pulled out of the thread passage of the looper by the movement of 120 the usual take-up 110, but will remain in the opening 106 of the thread clamp. The operation of the cam 102 and the lever 96, 98 moves the thread clamp down against an abutment 112 (Fig. 4) upon the machine 125 130

frame and clamps the free end of the thread in the opening 106 between the abutment and the clamping lever 90. Any excess movement of the lever 96, 98 will be taken up by the compression spring 114 which is mounted on the link 94 between a collar 116 on the link and the lower end of the lever arm 96.

The cams which actuate the looper threading mechanism are operated by a half-revolution clutch which will be hereinafter termed the "cam clutch". In one half revolution of the cam clutch, the looper threading mechanism is operated, and upon the following half revolution the looper threading mechanism is retracted to its normal inoperative position. To drive the cams a worm wheel 118, which meshes with teeth on the gear wheel 104, is mounted upon the lower end of a clutch shaft 120 that is journaled in the auxiliary frame 82. A clutch pulley 122 is loosely mounted on the upper end of the shaft 120 and is continuously driven by a belt 124 which runs between the pulley 122 and a pulley 126 on a continuously driven reversing shaft 128. The reversing shaft 128 is the same as that shown in the patent to Topham No. 1,099,326, dated June 9, 1914, and is employed in stopping the machine and bringing the stitch forming devices to rest in a predetermined position, all of which is fully described in said patent. A clutch member 130 is splined to the shaft 120 and is normally moved into position to be locked to the pulley 122 by means of springs 132. The clutch member 130 is moved out of clutching position by a clutch lever 134 which is controlled by a latch 136 that is operated by the gear wheel 104. The lever 134 is pivoted to the frame 82, and its upper yoke end engages an annular groove 137 in the member 130. The latch 136 is pivoted to the lever 134 and has a downwardly projecting dog 138 which is adapted to engage pins 139 mounted in the face of the gear wheel 104. A tension spring 140 is connected between the machine frame and the end of the latch 136 which tends to draw the latch and dog down into engagement with the pins 139. The direction of rotation of the gear wheel 104 is such that the clutch lever 134 will disconnect the member 130 from the pulley 122 when a pin 139 engages the dog 138.

Whenever the thread is broken the operator stops the machine and may then throw the looper threading mechanism into operation without removing the shoe from the shoe feeding and supporting devices. The looper threading cam clutch is thrown into operation by means of a hand lever 142 (Figs. 1, 2 and 5) which is mounted at the front of the machine frame in a position convenient for the operator. An arm 144

projects inwardly from the pivot 146 of the lever 142 and a lug 148 is formed on the end of the arm 144 in position to engage the lower end of a foot 150. The foot 150 is pivoted to a releasing bar 152 slidably mounted in the frame 82, and provided with a dog 154 which engages the lower face of the latch 136. Through these connections the latch 136 will be lifted from the pin 139 with which it is in engagement, whenever the hand lever 142 is moved inwardly (Fig. 5). When the latch 136 is lifted, the springs 132 will move the clutch member 130 into engagement with the pulley 122, and the cam disk 60 will be rotated until the dog 138 of the latch 136 is again engaged by a pin 139 to disconnect the member 130 from the pulley 122. The hand lever 142 is acted upon by a spring-pressed plunger 160 and its outward position is determined by the engagement of an abutment 156 on the lever with a hook 158 mounted in the machine frame. The inward movement of the hand lever, when connecting the cam clutch, is limited by the engagement of a lug 162 on the hand lever with an abutment 164 on the machine frame.

The looper threading mechanism is locked in an inoperative position during the sewing operation. To this end a detent 166 (Figs. 2 and 5) is formed on the lever 168, which stops the reverse rotation of the main cam shaft 172 of the machine and which is actuated during the reverse rotation of the cam shaft as the machine stops by means of the lever 170, as fully explained in Patent No. 1,099,326 above referred to. During the sewing operation the stop lever 168 is held in a position where the detent 166 is in front of a lug 167 on the back of the lever 142 so that the lever cannot be moved to throw the looper threading mechanism into operation. When the machine is stopped and the cam shaft 172 reversed, the detent 166 is moved from behind the lug 167 to the position shown in Figs. 2 and 5, so that the hand lever 142 may be operated to throw the looper threading mechanism into operation.

When the machine is stopped in position for the looper threading mechanism to be thrown into operation, the thread tension is released so that the thread may be freely drawn for the looper threading operation.

The tension releasing mechanism is substantially the same as that disclosed in the patent to Eppler above referred to, and consists of an arm 173 projecting from the lever 168, a rod 174 pivotally connected to the arm 173, a brake lever 176 carrying a brake shoe 178 and arranged to be acted upon by a collar on the rod 174, a brake drum 180 on the shaft of the tension wheel, and springs 182 acting on the brake lever 176.

When the looper threading mechanism is thrown into operation the operating cams 130

will make one-half a revolution and stop, leaving the thread arm 63 and thread clamp 90 in the position shown in Fig. 4. After the looper has been threaded the machine 5 may be thrown into operation and the operation of the sewing machine will automatically restore the looper threading mechanism into inoperative position. To accomplish this a pin 184 on the arm 98 of the 10 actuating lever of the thread clamp projects into a slot 186 on the foot 150 of the releasing slide 152. When the lever 96, 98 is operated to clamp the thread end, the foot 150 (Fig. 5) will be moved into a position 15 above a lug 188 formed on the side of a cam lever 190 which is movable about the pivot 146. The cam lever 190 carries a roll 192 which works in a cam groove in a cam on the shaft 172. As the machine is started up 20 to form the first stitch the lever 190 is raised, carrying with it the slide 152 and lifting the latch 136 to connect the cam clutch. The cam clutch will then make a half revolution and be again stopped by the engagement 25 of the latch 136 with a pin 139 on the gear 104. During this motion of the clutch the looper threading mechanism will be withdrawn to inoperative position and the dog 150 will be shifted back so as to rest above 30 the abutment 148 on the arm 144.

While the looper threading mechanism is in operation, the sewing machine is locked in an inoperative position. To accomplish this a three-arm locking lever 194, Fig. 2, is 35 pivoted on the frame 82 and has an arm 196 which is held in engagement with the lower end of the clutch lever 134 by a tension spring 198, which is connected between the lever 194 and the machine frame. When the 40 clutch lever 134 is moved by the springs 132 in connecting the cam clutch, a pawl 200 on the lever 194 will be moved into engagement with the teeth 202 formed on the peripheral edge of a cam 204 on the shaft 172. 45 This pawl 200 will prevent rotation of the cam shaft 172, while the looper threading mechanism is in operation. When the cam clutch is disconnected, the pawl 200 will be withdrawn from the teeth 202 so that the 50 sewing machine may be placed in operation.

The locking lever 168 and reversing lever 170 are shown in Figs. 2 and 5 in the position which they assume when the machine has been stopped with the stitch-forming devices in the predetermined position. At 55 this time it will be noted that a pin 206 at the pivot of the levers 168 and 170 is withdrawn from a face 208 on the locking lever 194. This will permit the lever 194 to be 60 moved to bring the pawl 200 into contact with the teeth 202 when the cam clutch is thrown in. At the time the cam clutch is connected to restore the looper threading mechanism to inoperative position the reversing lever 170 has been moved down- 65

wardly in starting the sewing machine, and the pin 206 will come into engagement with the face 208 on the lever 194. Therefore, when the cam clutch is operated through the cam lever 190, the pin 206 will prevent the lever 194 from being rotated so that the pawl 200 will not engage the teeth 202. With this construction the pawl 200 will only be placed into locking engagement with the cam 204 when the sewing machine 70 is stopped and the looper threading mechanism is put into operation by the hand lever 142.

As the thread passes to the sewing point it runs over a thread tension wheel 210 around 80 a thread truck 212 on the machine frame, and a thread truck 214 on the take-up 110. In the sewing machine shown in the Eppler patent an auxiliary take-up is located between the thread trucks 212 and 214, but it 85 will be seen from the drawings that the thread arm 63 and thread clamp 90 operate in the position ordinarily occupied by the auxiliary take-up, and that the auxiliary take-up is omitted. To provide an auxiliary 90 take-up movement for the thread the thread tension in the illustrated embodiment of the invention is constructed to have the auxiliary take-up motion. The thread tension shown in Figs. 8 and 9 consists of a tension wheel 95 210 which is connected to a brake shaft 218 by means of two tension springs 220 and 222. The wheel 210 is attached to the flange of a sleeve 224 which is loosely mounted upon the shaft 218. A flange 226 is formed on the shaft 218 and carries a pin 228 which projects through a slot 230 formed in the wheel 210 and sleeve 224. One end of the spring 222 is secured to the pin 228 and the other end of the spring is fixed in a collar 232 which is fixed on the shaft 218. One end of the spring 220 is fastened to a pin 234 mounted in the wheel 210 and sleeve 224, and the other end of the spring 220 is fixed in a collar 236 which is secured to the shaft 100 218. With the above construction the operation of the thread tension is as follows: When the brake 178 is removed from the drum 180 on the shaft 218, the tension wheel 210 will move freely with the shaft and the 105 thread can be drawn off. When the brake is acting on the drum 180 a pull on the thread will tend to rotate the tension wheel relatively to the shaft, first against the action of the spring 220 until the pin 234 has 110 been moved into contact with the end of the spring 220, then against the action of both springs 220 and 222 until the edge of the slot 230 in the tension wheel comes into contact with the pin 228. At this time the tension wheel will move with the brake shaft to give off thread. If slack thread is given by the stitch forming devices while the tension wheel is held by the springs 220 and 222, the thread will be taken up by the 115 120 125 130

action of the springs. With this construction the thread tension, in addition to its usual operation, has a take-up motion similar to that usually produced by known forms 5 of auxiliary take-up levers and associated spring buffers.

Although the above thread tension is of special advantage in a machine employing a looper re-threading mechanism, obviously 10 the improved thread tension may be embodied in almost any type of wax thread sewing machine.

This thread tension forms the subject matter of a divisional application filed June 24, 15 1919, Serial No. 306,475.

It will be seen that excess thread is used in threading the looper, and if the tension is locked when the take-up 110 moves up in the formation of the first stitch after threading 20 the looper, the thread will probably be broken. For this reason, when the cam clutch is thrown into operation to withdraw the looper threading mechanism to inoperative 25 position, the thread tension is released during the formation of the first stitch. To accomplish this, a rod 238 at the back of the machine projects through an opening in the brake lever 176 and has a collar 240 fast thereon which is adapted to engage the lever 30 and move it against the action of the springs 182. The rod 238 is connected with one arm of a bell crank lever 242, which is pivoted in the auxiliary frame 82. A cam roll 244 is mounted on the other arm of the bell crank 35 lever 242, and is held in contact with the surface cam 58 on the cam disk 60 by means of a tension spring 246, which is connected between the lever 242 and the machine frame. With this construction, when the cam 60 is 40 making its half revolution to withdraw the looper threading mechanism to inoperative position, the tension will be released only during the formation of the first stitch.

The operation of the machine is as follows: A shoe is presented to the shoe supporting and feeding devices, and the sewing operation is performed in the usual manner. If the thread breaks, the operator will stop the machine, and push in the hand lever 142 to connect the cam clutch. When the cam clutch is thrown into operation, the wedge 40 will be moved down to open up the looper passage, the thread clamp 90 will be moved back to clamp the free end of the 50 thread against the abutment 112, and the thread arm will be moved down behind the looper to place the thread in the looper passage. The wedge will then be moved up to close the looper passage, and the looper 55 is in condition to continue the sewing operation. When the machine is stopped, the brake 178 is removed from the tension so that the thread is free to be drawn off in threading the looper. As the cams complete 60 their first half revolution in threading

the looper, the pawl 200 will be withdrawn from the teeth 202 of the cam 304 and the operator may then start the sewing operation. At the commencement of the sewing operation, the cam clutch will be thrown 70 into operation by the lever 190, and the cams 60 and 104 will be given a half revolution to draw up the thread arm and move the thread clamp out into the path of the thread. As the thread clamp is moved out, the thread 75 will be under tension and will be forced against the spring 68 and into the passage 106 in the thread clamp. While the first stitch is being formed the thread arm 63 will not be withdrawn from behind the 80 looper and the thread hook 64 will act in the same way as the usual thread finger 14 in forming the stitch. At the time the cams have completed their second half revolution the looper threading mechanism will be 85 withdrawn into inoperative position and be ready to be thrown into operation to thread the looper, by the hand lever 142.

The preferred embodiment of the invention having been thus described, what is 90 claimed as new is:

1. A sewing machine, having in combination, stitch forming devices including a hooked needle and a looper and means normally inoperative during the sewing operation for threading the looper.

2. A sewing machine, having in combination, stitch forming devices including a hooked needle and a looper having a thread passage and means acting automatically, 100 when thrown into operation, to place a thread in said passage.

3. A sewing machine, having in combination, stitch forming devices including a hooked needle and a looper, a looper threading mechanism normally inoperative during the sewing operation and acting when thrown into operation to thread the looper while the stitch forming devices are at rest.

4. A sewing machine, having in combination, stitch forming devices including a hooked needle and a looper, a looper threading mechanism, means for throwing said mechanism into operation, and means for preventing the operation of said mechanism until the stitch forming devices have come to a stop in a predetermined position.

5. A sewing machine, having in combination, stitch forming devices including a hooked needle and a looper, a looper threading mechanism, and means to lock the threading mechanism in inoperative position during the sewing operation.

6. A sewing machine, having in combination, stitch forming devices including a hooked needle and a looper, a looper threading mechanism, and means to prevent the stitch forming devices from being thrown into operation during the looper threading operation.

7. A sewing machine, having in combination, stitch forming devices including a hooked needle and a looper, a thread tension, means for threading the looper, and means for releasing the tension on the thread during the looper threading operation.

8. A sewing machine, having in combination, stitch forming devices including a hooked needle and a looper, a thread tension, means for threading the looper, means for releasing the tension on the thread during the looper threading operation, and means for holding the tension released during the formation of the first stitch thereafter.

15 9. A sewing machine, having in combination, stitch forming devices including a looper having a thread passage formed of relatively movable sections, mechanism for placing a thread in the passage, and means to relatively move the sections of the looper thread passage to open the passage before the thread is placed therein, and to close the passage after the thread has been placed therein.

25 10. A sewing machine, having in combination, stitch forming devices including a

looper having a thread passage therein, a looper threading mechanism comprising means for holding the free end of the thread, devices for opening and closing the thread passage and a thread arm for placing thread in the passage.

30 11. A sewing machine, having in combination, stitch forming devices including a looper having a thread passage formed of movable sections, and looper threading mechanism comprising means for holding the free end of the thread, devices for opening and closing the thread passage, a thread arm for placing thread in the passage, and a series of cams for actuating the members of the looper threading mechanism, and means including a clutch for controlling the rotation of the cams.

35 12. A sewing machine, having in combination, stitch forming devices including a looper, a looper threading mechanism, and means to operate the threading mechanism to thread the looper while the shoe remains in sewing position.

40 WILLIAM THOMAS BUCKINGHAM ROBERTS.
